United States Patent

Des. 241,728
Patented Oct. 5, 1976

241,728

WATCH DIAL

Maurice Etienne, Granges, Switzerland, assignor to
Fortis S.A.

Filed July 29, 1974, Ser. No. 492,764

Claims priority, application Switzerland Jan. 31, 1974

Term of patent 14 years

Int. Cl. D10—07

U.S. Cl. D10—123

Fig.1

Fig.2

Fig 3

FIG. 1 is a front elevational view of a watch dial showing my new design;

FIG. 2 is a front elevational view of another embodiment of my new design of FIG. 1; and

FIG. 3 is a front elevational view of yet another embodiment of my new design of FIG. 1.

The rears of the designs are plain and unornamented and of no appreciable thickness.

I claim:

The ornamental design of a watch dial, substantially as shown.
